UNITED STATES PATENT OFFICE

THOMAS A. KEMP, OF KANSAS CITY, MISSOURI, ASSIGNOR TO THE LONG-BELL LUMBER COMPANY, OF KANSAS CITY, MISSOURI, A CORPORATION OF MISSOURI

WINDOW FRAME

Application filed August 25, 1930. Serial No. 477,631.

This invention relates to wood window frames, and has for its object to produce a window frame which is weatherproof at every exposed joint, and of simple, durable and inexpensive construction. More specifically my object is to produce a window frame in which all exposed joints are of interlocking type to prevent air, water and dust leakage, and in which all parts are standardized so that corresponding parts are interchangeable to facilitate and minimize the expense of assemblage.

With this general object in view, the invention consists in certain new and useful features of construction and combinations of parts as hereinafter described and claimed; and in order that it may be fully understood, reference is to be had to the accompanying drawings, in which:

20 Figure 1 is a sectional perspective view of an upper corner of a window frame embodying the invention, as employed in frame houses.

25 Figure 2 is a sectional perspective view of the lower corner of a window frame embodying the invention, for frame houses.

Figure 3 is a fragmentary perspective view of the sill for use in a window frame for frame houses.

30 Figure 4 is a fragmentary perspective view of the sill and a pulley stile in interlocked relation.

Figure 5 is a fragmentary perspective view of the pulley box construction of the window for use in masonry houses.

35 Figure 6 is a fragmentary perspective view of the sill for use in a window frame for masonry houses.

Figure 7 is a fragmentary horizontal section taken through a pulley box of the window frame for use in masonry houses.

40 Figure 8 is a horizontal section showing a mullion assembly for use in both types of window frames.

45 Referring now to the drawings in detail, and first to the type of construction of a window frame for frame houses, 1 denotes the sill which slopes downwardly and outwardly, as conventional, and is provided at its upper side and for its full length with

an inner outwardly-facing shoulder 2 and an outer outwardly-facing shoulder 3. The sill is of the double horn type at each end, the inner horns 4 projecting beyond the ends of the body portion of the sill with their outer faces coincidental with the shoulder 3, and with the inner faces of the outer horns 5, the latter projecting laterally beyond the horns 4 and having their upper faces occupying a lower plane. The opposite faces of the body portion of the sill are parallel and in the under side of the sill are provided inwardly-facing inner and outer shoulders 6 and 7, and downwardly-opening grooves 8 and 9.

55 Pulley stiles 10 abut against and are secured to opposite ends of the sill, having grooves 11 conforming to and receiving the respective ends of the sill, and said pulley stiles are connected at or near their upper ends by the head jamb 12, which jamb in conjunction with the pulley stiles 10 and the sill constitute a rigid rectangular frame. 60 The pulley stiles are provided with vertical grooves 13 containing the parting stops 14, and the head jamb is provided at its under side with a groove 15 receiving the upper 65 parting stop 16, the same engaging the upper ends of the parting stops 14.

70 The outer edges of the pulley stiles 10 are provided with tapered grooves 17 and abutting against said edges and fitting down upon the sill at the inner ends of horns 4 are vertical side blind stops 18, said stops having vertical wedge tongues 19 snugly fitting the 75 grooves 17. A head blind stop 20 fits against the outer edge of the head jamb and bears at its opposite ends against and is secured to the side blind stops 18 and is provided at its inner side with a horizontal wedge tongue 21 engaging a corresponding groove 22 in

80 the outer edge of the head jamb 12. Vertical side casings 23 fit upon the sill and against the side blind stops and are provided with vertical tapered grooves 24 snugly receiving vertical wedge tongues 25 on the outer faces 85 of the side blind stops. Fitting upon the upper ends of the side casings, is a head casing 26 provided at its lower edge with a tapered groove 27 snugly receiving corresponding wedge tongues 28 on the upper ends 90 of the side casings. Fitting upon the upper ends of the side casings, is a head casing 26 provided at its lower edge with a tapered groove 27 snugly receiving corresponding wedge tongues 28 on the upper ends 95 of the side casings. Fitting upon the upper ends of the side casings, is a head casing 26 provided at its lower edge with a tapered groove 27 snugly receiving corresponding wedge tongues 28 on the upper ends 100

of the side casings 23. The head casing is also provided in its inner face with a horizontal tapered groove 29 snugly receiving a corresponding wedge tongue 30 formed on the outer face of the head blind stop 20, the tongues 21 and 30 of the head blind stop being preferably horizontally offset. A drip cap 31 is mounted on the upper edge of the head casing 26, and is provided at its under side with a rabbet or groove 32 snugly fitting said head casing, and outward of the latter with a water-drip groove 33 to serve as a water drip.

The pulley stiles 10 are provided in their outer faces with vertical grooves 34 receiving the adjacent edges of the ground pieces 35 forming the inner walls of the pulley boxes, of which the outer walls are constituted by the studs 36. The remaining features disclosed by Figures 1 and 2 are conventional and are simply identified by the following reference characters. A indicates building paper at the outer sides of the sheathing B fastened to studs 36 and at the upper end of the casing to the plates or studs E. C represents lathing and D plaster. F represents back bands and G, inside casing. H indicates inside stops and J the stool and K the apron.

Referring now to a window frame for use in masonry houses, it will be noted that the sill 37 has the shoulders 38 and 39 corresponding to shoulders 2 and 3, and that between said shoulders the body portion of the sill is prolonged or extended as at 40, the outer edges of the extensions being disposed inward of the shoulder 3. The prolongations of the body portion of the sill provide inner and outer notches 41 and 42, the former of greater length than the latter, and communicating with the inner ends of notches 41 are grooves 50 formed in the upper side of the body portion of the sill and having bottoms which taper from the upper surfaces of the sill adjacent shoulder 39 to the opposite edge of the sill, these grooves receiving the inner side walls or stiles 51 of the pulley boxes. The pulley boxes consist of parallel spaced pulley stiles 51 and walls 52, inner walls 53 and exterior walls 54, the walls 52 to 54 inclusive depending to a lower plane than wall or stile 51, which fits snugly in the groove 50. The inner wall 53 fits in notch 41 and wall 54 is stepped at its lower end so as to rest upon the sill coincident with the shoulder 39 and to extend down into the notch 42 where it abuts against and is secured to the wall 52, and said wall 54 is provided in its inner face with a tapered groove 55 receiving a corresponding wedge tongue 56 on the outer edge of the pulley stile 51, and secured to the outer side or face of the wall 54, is a brick mold 57. It will be noted by reference to Figures 5 and 7, that a vertical space is provided between the wall 54 and the abutting side cas-

ing 57 by making the inner portion of wall 54 of increased thickness, this space being provided for the accommodation of water-proof building paper and mortar seal. In the respects mentioned, that is in the detail construction of the sill and in the use of a four-wall pulley box, lies the only real difference of construction between the window frame for masonry houses and the window frame for frame houses, and it is therefore believed that it is unnecessary to duplicate the showing of the upper part of the window frame for masonry houses or to describe the same in detail, as the showing and description of the upper part of a window frame for frame houses applies equally well to the frame for masonry houses. For windows provided with a mullion, the latter consists of a vertical box 58 of which the outer wall 59 is provided with vertical tapered grooves 60 in its inner face receiving corresponding tongues 61 on the outer edges of the side walls of the box, and fastened to the outer face of the wall 59 is a casing 62 which matches the side and head casings and extends from the latter to the sill as customary. The juxtaposed faces of the wall 59 and casing 62, are channelled at 63 to provide an air space serving to prevent cupping or warping of said parts.

The grooves on the pulley stiles engaged by the ends of the sill in the window frame for frame buildings constitute dadoes to prevent air and water leakage at such points, and, while not so shown, the head jamb in the wood construction also has dado connections with the opposing or inner faces of the pulley stiles for the same reason. The grooves formed by and between the inner shoulder 2 of the sill and the parting stops of course receive the lower sash, not shown, and the spaces between the parting stops and the outer blind stops provide the grooves for the reception and operation of the outer sash, not shown, and the various wedge-shaped tongue and groove connections at every exposed joint constitute interlocks to prevent air, water and dust leakage, as well as impart to the window frame greater strength, rigidity and durability. The outer shoulder on the upper surface of the sill,—which is pitched to insure free drainage,—affords a water proof joint or abutment for a storm sash, not shown. The provision of the double horns provides for a connection therewith of the blind stops and the inner sides of the side casings which is water proof, and the sill has parallel upper and lower faces to insure tight joints for the entire width of the jamb. The water drip grooves on the drip cap and sill are to prevent water from backing up, and the groove 8 in the bottom of the sill is for the reception of the underlying siding.

As a whole the casing not only is thor-

oughly water proof and of strong and durable construction, but it is also of economical construction as the parts can be readily and easily assembled. This casing is believed to be the first completely air-tight or water-tight wood window frame, and it has gone into very extensive use.

From the above description, it will be apparent that I have produced a window frame embodying the features of advantage set forth as desirable in the statement of the object of the invention, and which may be modified in minor particulars without departing from the spirit and scope of the appended claims.

I claim:

1. In a window construction, a sill having an inner longitudinal shoulder facing outwardly and provided at each outer corner with a pair of longitudinally-extending parallel horns, the inner horns terminating short of the outer horns and being flush at their upper sides with the upper surface of the sill and having unbroken connection there-

with, and the outer horns having upper surfaces lower than the inner ones and the upper surface of the sill outward of the inner horns.

2. In a window construction, a sill having an inner longitudinal shoulder facing outwardly and provided at each outer corner with a pair of longitudinally-extending parallel horns, the inner horns terminating short of the outer horns and being flush at their upper sides with the upper surface of the sill and having unbroken connection therewith, and the outer horns having upper surfaces lower than the inner ones and the upper surface of the sill outward of the inner horns, in combination with vertical stiles corresponding in width to that of the sill minus the horns, and fitting at their extreme outer edges against the inner vertical faces of the inner horns and having downwardly and outwardly sloping grooves in their inner faces receiving the end extremities of the sill inward of said horns.

In testimony whereof I affix my signature.

THOMAS A. KEMP.
